UNITED STATES PATENT OFFICE.

RUFUS I. HEPBURN, OF PORTLAND, OREGON.

TOY FIREPLACE.

No. 856,060.

Specification of Letters Patent.

Patented June 4, 1907.

Application filed March 4, 1907. Serial No. 360,559.

To all whom it may concern:

Be it known that I, RUFUS I. HEPBURN, a citizen of the United States, residing at Portland, in the county of Multnomah and State 5 of Oregon, have invented a new and useful Improvement in Toy Fireplaces, of which the following is a specification, reference being had to the accompanying drawings.

My invention relates to improvements in 10 toy fire-places.

The object of my invention is to provide a movable toy fire-place which may be folded up and compactly stored when not in use and at the same time may be set up next to the 15 wall of a room in such position as to resemble a fire-place and to be used for children at Christmas and holiday times or whenever a toy fire-place might be used for show or entertainment. I attain these objects and 20 other advantages, by the construction, combination and arrangements of parts illustrated in the aforesaid drawings.

It is well known that at Christmas and 25 holiday times in houses or show windows or for entertainments, it is necessary to quickly make up an imitation fire-place in which the stockings of children may be hung or down which Kriss Kringle may come. No convenient or practical device has heretofore 30 been invented to accomplish such objects as my invention does, nor anything which may be carried as stock merchandise at all times to be sold at a low price.

Figure 1 is a front perspective view of the 35 toy fire-place set up in position for use. Fig. 2 is a rear perspective view of the vertical parts and inside top piece of the same unfolded. Fig. 3 is an inverted plan view of the top piece. Fig. 4 is a plan view of the 40 bottom piece.

Like letters refer to like parts throughout the views.

In Fig. 2 are seen the rear of the front part C, the front of the back part D, the lower side 45 of the top or flue piece E, having therein the flue opening e, the inner side walls a a', the outer side walls b b' and the flap or rear corner

securing piece c. Figs. 2, 3 and 4 show all the component parts which make up the fireplace as appears in Fig. 1.

In Fig. 1 are shown a top or mantle piece A, the front of the rear piece D, inside wall a, outside wall b', the front piece C and the bottom piece B, all in set up position of the fireplace. The parts C, D, E, a a', b b', and c are 50 joined together with hinges d of cloth, leather or any suitable hinge. The parts of my device may be made of card-board, tin or any suitable light material and painted or decorated to resemble a fire-place.

In Fig. 2 are set up against the wall of a room as appears in Fig. 1, over the bottom piece B, and having been brought into rectangular position, are secured at the rear 55 corner by the flap c. The inner side pieces a a' may be secured in proper position by cleats underneath the flue piece E, or in any other suitable way, and the said flue piece dropped over them in its place. The mantle 60 piece A is placed on top as shown and the fire-place is then in set up position as it is intended to be for the objects and purposes herein specified.

Now having described my invention, I do 75 not limit myself to any particular size, style of a fire place or to the kind of material or decoration of the same, nor the exact number of parts to be hinged together to make up the device.

I claim:

A toy fire-place comprising folding, vertical front and back parts C, D, inner side walls a a', outer side walls b b', a flue piece E, provided with a flue opening e, a mantle piece A 85 and bottom piece B, all of suitable light material, having means to secure the same in fire place form, and having suitable fire-place decoration thereon, all substantially as described.

RUFUS I. HEPBURN.
